Primary Examiner — Clare E Heflin(74) *Attorney, Agent, or Firm* — Marshall, Gerstein & Borun LLP**CLAIM**

The ornamental design for a lighting fixture, as shown and described.

DESCRIPTION

FIG. 1 is a perspective view of a lighting fixture showing the new design angled rearward approximately 15 degrees from vertical;

FIG. 2 is a side elevation view thereof, with all side elevation views being identical; FIG. 3 is a bottom plan view thereof; FIG. 4 is another perspective view thereof showing the design angled rearward approximately 30 degrees from vertical; and, FIG. 5 is another perspective view thereof showing the design angled rearward approximately 45 degrees from vertical.

The broken lines showing portions of the lighting fixture are included for the purpose of illustrating environment and form no part of the claimed design.

1 Claim, 3 Drawing Sheets(56)
